UNITED STATES PATENT OFFICE.

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE.

COAL MOISTENER FOR STOKERS.

Application filed June 4, 1926. Serial No. 113,797.

This invention relates to locomotive stokers and has for its principal object to provide simple apparatus for moistening the coal handled by the stoker and to provide a pressure feed water system that will deliver water in direct proportion to the rate of firing.

Further objects and advantages of the invention will become apparent as the disclosure proceeds and the description is read in connection with the accompanying drawings, in which

Fig. 1 is a rear elevation of a locomotive equipped according to the invention;

Fig. 2 is a sectional view on the line 2—2 of Fig. 1;

Fig. 3 is a sectional view on the line 3—3 of Fig. 2;

Fig. 4 is a plan view of a control valve;

Fig. 5 is a vertical section of the same;

Figs. 6, 7 and 8 are horizontal sections

through the valves showing different positions;

Fig. 9 is a side elevation of the adjacent portions of the tender and the locomotive with the invention applied thereto;

Fig. 10 is a vertical section taken on the line 10—10 of Fig. 9;

Fig. 11 is a vertical section taken on the line 11—11 of Fig. 10;

Fig. 12 is a side elevation of adjacent portions of a locomotive and its tender with a modified form of the invention applied to them;

Fig. 13 is a plan view of the tender corresponding to Fig. 12.

The general organization is shown in Figs. 1 and 9, in which 10 indicates the back head of the locomotive, 11 the deck of the cab, and 12 the deck of the tender.

The stoker illustrated includes a transfer screw conveyor 13 for bringing the coal from the tender to the locomotive and a plurality of screw elevators 14 for raising the coal to

an elevation suitable for scattering over the grates (not shown). The conveyors are driven by a relatively small multi-cylinder engine 15, mounted below the deck 11 and equipped with suitable gearing for driving

the several conveyors. This gearing includes a shaft 16 extending transversely across the locomotive adjacent to the juncture of the three screws and equipped adjacent to its end with an eccentric 17 (Fig. 9), cooper-

ating with a strap 18 to drive a pump, diagrammatically illustrated, by the piston 19, and a cylinder 20 equipped with an inlet valve 21 and an exhaust valve 22. The inlet valve is connected by a pipe 23 with the tank carried by the tender. The outlet valve 22 is connected by a pipe 24 with the valve casing 25 which, in turn, is connected by pipes 26 with the casings of the elevators 14.

The valve casing 25 has a flange 260 adapted to be secured to the back head of the locomotive, or any other suitable support. Within the casing is a chamber or bore 27 entered through the bore 28 of a plug 29 which receives the pipe 24. The chamber 27 communicates with outlet chambers 30 and 31 (Figs. 6, 7 and 8) through ports 32 and 33 divided by ribs 34. These ports are controlled by a valve 35 rotatably mounted in the casing and equipped with a semi-cylindrical skirt 36 adapted to take the positions shown in Figs. 6, 7 and 8, and a variety of positions between those, by which the flow through the several pipes may be controlled and varied to suit the requirements.

The valve 35 has a stem 37 fixed to a collar 38 by a nut 39 and a key 40. The collar carries a pivoted hand lever 41 having a pawl 42 adapted to engage a rack 43 to hold the valve in a selected position. A spring plunger 44 serves to hold the pawl in engagement with the rack. When the valve is in the position shown in Fig. 6, water is freely and equally admitted to both the pipes 26. When it is in the position shown in Fig. 7, water is admitted to one pipe only, and when it is in the position shown in Fig. 8 water is admitted to the other pipe only.

The pipes 26 are connected with the casings of the elevators 14 through jackets 45, which provide elongated passages 46 extending upwardly from openings 47 in the walls of the casings. Thus the water passages are offset adjacent to the elevators and traps are formed to prevent fine coal, or dust, from clogging the pipes. Plugs 48 are provided to admit a tool for clearing the traps.

Provision is also made for supplying moisture to the fuel while it is passing through the transfer conveyor. This may be accomplished by connecting the pipe 24 with the pipe 49 (Fig. 9) leading to a spray 50, lying over a slot 51 in the casing 52 of the transfer conveyor 13.

A suitable valve 53 at the juncture of the pipes 24 and 49 will permit the water to be sent to its transfer conveyor only, or the elevators only, or part to each, as may be desired.

In the modified form shown in Figs. 12 and 13, the pump 54 delivers to a pipe 55 which branches at 56 and delivers to a plurality of sprays 57, arranged along the upper margins of the coal bin on the tender.

As here shown, the sprays are arranged along the sides 58 of the bin and just back of tool boxes, 59. Ordinarily it would be objectionable to obstruct the bin from the front, because when the coal boards 60 are removed the fireman should be able to freely enter the bin.

I claim as my invention:

1. The combination of a locomotive, a tender, stoking mechanism for firing the locomotive with fuel carried by the tender, an engine for driving the stoking mechanism and means driven by said engine for moistening fuel uniformly as it is supplied by the stoking mechanism.

2. The combination of a locomotive, a tender, stoking mechanism for firing the locomotive with fuel carried by the tender, an engine for driving the stoking mechanism and located at one side of the locomotive below the deck, a pump at the opposite side of the locomotive from the engine, transmis-

sion mechanism connecting the engine and the pump and means connected with the pump for moistening the coal.

3. The combination of a locomotive, a tender having a bin for coal and a tank for water, stoking mechanism including a conveyor for coal, an engine driving the conveyor, and a pump driven by the engine for supplying water to the coal.

4. The combination of a locomotive, a tender having a bin for coal and a tank for water, stoking mechanism including a conveyor for coal, an engine driving the conveyor, a spray for the bin, and a pump driven by the engine for supplying the spray.

5. The combination of a locomotive, a tender having a bin for coal and a tank for water, stoking mechanism including a conveyor for coal, an engine driving the conveyor, a spray for the bin including a plurality of perforated conduit sections, a pump driven by the engine for supplying water to the spray.

6. The combination of a locomotive, stoking mechanism for supplying fuel to said locomotive, and means for automatically supplying moisture in liquid form to said fuel in proportion to the amount of fuel supplied to said locomotive.

In testimony whereof I affix my signature hereto.

NATHAN M. LOWER.
